(57) **CLAIM**

The ornamental design for a clamp pad guard for a lift truck or the like, as shown and described.

DESCRIPTION

FIG. 1 is an isometric view from the upper left front of a clamp pad guard for a lift truck or the like, including my new design, wherein the shading of the eagle-shaped portion is intended to represent an opening extending entirely through the clamp pad guard;

FIG. 2 is a front elevational view thereof;

FIG. 3 is a left end elevational view thereof;

FIG. 4 is a right end elevational view thereof;

FIG. 5 is a top plan view thereof; and,

FIG. 6 is a rear elevational view thereof, the bottom of the clamp pad guard not including any part of the design.

Lower portions of the clamp pad guard are shown in broken line in FIGS. 1-4 and 6 and are included merely for illustrative purposes and form no part of the claimed design. The broken lines immediately adjacent to the shaded areas at the bottoms of the drawing views represent unclaimed boundaries of the design.

The shapes of the left end, top, and right end of the clamp pad guard are shown in broken line and are included merely for illustrative purposes and form no part of the claimed design. The broken lines immediately adjacent to the areas in FIGS. 1, 2, and 6 that are shaded in solid line represent unclaimed boundaries of the design.

The eagle shape of the opening as shown in FIGS. 1 and 2 and in reversed form in FIG. 6 is part of a trademark of Cascade Corporation, an Oregon corporation.

1 Claim, 3 Drawing Sheets
